UNITED STATES PATENT OFFICE.

ISAAC SNOW, OF LAWRENCE, MASSACHUSETTS, ASSIGNOR TO DRAPER CORPORATION, OF HOPEDALE, MASSACHUSETTS, A CORPORATION OF MAINE.

FEELER-MOTION FOR LOOMS.

1,378,907.

Specification of Letters Patent. Patented May 24, 1921.

Application filed July 9, 1919. Serial No. 309,596.

To all whom it may concern:

Be it known that I, ISAAC SNOW, a citizen of the United States, residing at Lawrence, in the county of Essex and State of Massachusetts, have invented an Improvement in Feeler-Motions for Looms, of which the following description, in connection with the accompanying drawings, is a specification, like characters on the drawings representing like parts.

This invention relates to feeler motions for looms, whereby the loom may be stopped or the filling replenished when the filling in the working shuttle becomes substantially, though not fully exhausted, and more particularly the invention relates to improvements in feeler motions of the rotary type, such, for instance, as shown and described in United States patent to Thomas Ferguson, No. 1,225,120, dated May 8, 1917.

Feeler mechanisms of this type, to be practically efficient, must be sufficiently sensitive to detect the condition of the filling in the working shuttle on each detecting beat of the lay and set in operation the train of mechanism to effect replenishment of filling only when that in the shuttle has become nearly exhausted. The feeler motion of the Ferguson patent has satisfactorily operated to this end, but owing to the different kinds or character of filling that may be employed, it frequently becomes necessary to adjust the parts connected to and operated by the feeler to maintain the sensitive response of the feeler to the kind or character of filling being used.

An important feature of the present invention, therefore, consists of a rotatable feeler having a resetting arm and an independently adjustable filling replenishing finger. In the practical accomplishment of this feature of the invention, the feeler may be formed with or have fixed thereto a resetting arm which coacts with a resetting cam independently of the finger which sets in operation the train of mechanism for replenishing the filling. The finger, which, for identification may be herein designated the replenishing finger, may be adjustably secured to or connected with the feeler separate from or independent of the resetting arm by means of a collar adjustable both rotatably and longitudinally of the feeler.

Different kinds of filling may require more or less adjustment of the spring which nor-

mally tends to rotate the feeler and maintain it in rearward position, and, at the same time, further adjustment of the replenishing finger may be necessitated to properly coordinate the parts and maintain the desired sensitive action of the feeler. Another important feature of the invention, therefore, consists in the independence of the spring and replenishing finger adjustment relative to the resetting arm.

The above and further novel features and combination of parts will be hereinafter described in connection with one good practical form of the invention, which will then be defined by the claims:

Figure 1 is a perspective view showing sufficient portions of the loom frame, the lay, and its associated parts, and the feeler, to make clear the characteristics of the invention;

Fig. 2 is an enlarged detached view showing the feeler and its operation when a working supply of filling is present in the shuttle on a detecting beat;

Fig. 3 is a view similar to that of Fig. 2 showing the action of the feeler when the filling has become substantially exhausted;

Fig. 4 is an enlarged end view of the engaging end of the feeler;

Fig. 5 is a side view of the end of the feeler showing the curved contour of the engaging end.

This invention is more particularly adapted for use in an automatic loom, wherein filling replenishment is effected when that in the active shuttle has become nearly or substantially exhausted; but it may, obviously, also be employed in connection with some other form of mechanism.

In the illustrated form of the invention, a loom frame is of any usual or desired character, and secured to the breast beam 1 is the transverse shaft 2, common in filling replenishing looms, and may be connected as usual to suitable means for causing filling replenishment when said shaft is rocked, all as will be readily understood by those skilled in the art. Secured to the transverse shaft 2 and extending upwardly therefrom is the usual arm 3 having pivotally connected thereto the arm 4 which, for identification, may be termed a latch or actuating latch, because by frontward movement thereof the transverse or change shaft 2 is rocked in opposition to the usual spring means for

holding the transverse shaft 2 and its connected parts in inoperative position. Rearward of the latch 4 is the operating member 5 which, as usual, may be either the weft hammer or a part connected thereto, and adapted to engage the end portion of the latch 4 on frontward movement of the operating member to cause the latch to be moved frontwardly and thereby rock the transverse shaft when the end of the latch is permitted to be positioned for engagement by the operating member. Pivotally mounted on a support 6 at 7 is the transmitter 8, the end 9 of which underlies the latch 4 and normally maintains the latch raised or in inoperative position. The other end of the transmitter has a shoe 10 which, as will later appear, is moved by the rotation of the feeler when, on a detecting beat, the filling is substantially exhausted.

The lay 11 carries the usual shuttle-box 12 for receiving the shuttle 13 which may be of usual or appropriate construction. The front wall of the shuttle-box is provided with a slot 14, and similarly the adjacent wall of the shuttle is provided with a slot 15, said slots coinciding when the shuttle is received into the detecting box at the detecting side of the loom.

The feeler of the present invention is of the rotary type and is carried by a feeler stand 16 preferably formed by a plate having upturned front and rear ends 17, 18, which constitute front and rear bearings for the feeler member. The bearings 17 and 18 are provided with a perforation through which the feeler member 19 passes and in which the feeler may move longitudinally and rotatively.

The feeler 19 may be variously contrived, but a convenient and good practical form of the feeler consists of a light metal cylindrical rod which may readily be passed through the perforations in the front and rear bearings when assembling the parts. The feeling end of the feeler, as indicated in Figs. 4 and 5 is provided with a series of projections or roughened portions 20 preferably arranged in a curve, as indicated in Fig. 5, approximating the cylindrical form of the filling carried by the bobbin 21.

The opposite end portion of the feeler 19 is provided with a setting arm 22 which may be secured to the feeler in appropriate manner, and as indicated is preferably formed integral therewith and bent laterally, such construction affording a cheap and simple embodiment of this feature of the invention. The feeler stand 16 has a frontwardly extending portion which is downturned to constitute a setting cam 23 adapted to be engaged by the setting arm 22 when the feeler is moved rearwardly into feeling position by the means presently to be described. The setting cam 23 has a front-

wardly projecting portion 24 which may serve as a stop to prevent undue rotative movement of the feeler when the filling is substantially exhausted on a detecting beat.

Mounted on the feeler 19 is a collar 25 which may be adjusted rotatively and longitudinally relative to the feeler and be secured in adjusted position by suitable means such as the set screw 26. Between the collar 25 and the front bearing 17 of the feeler stand is a spring 27, one end of which is secured at 28 to the feeler stand, and the other end of which is secured at 29 to the adjustable collar 25, the construction being such that by proper adjustment of the collar 25, the torsional and expansive force of the spring 27 may be adjusted to suit conditions of use, as for instance, when the character of yarn is changed in the shuttle.

Mounted on the feeler 19 is another collar 30 which is independent of the collar 25 and also independent of the setting arm 22. The collar 30 is independently adjustable longitudinally and rotatively relative to the feeler, and may be secured in desired adjusted position by suitable means such as the set screw 31. Secured to the collar 30 is the finger 32 which projects laterally from the collar, as indicated in Figs. 1 and 2. This finger 32 may, for the purposes of identification, be referred to as the replenishing finger, and is preferably downturned to provide an end portion 33 which normally underlies the step 10 of the transmitter 8, as indicated in Fig. 1.

From the construction described it will be apparent that the setting arm 22 which coacts with the setting cam 23 to restore the feeler to its proper rotative feeler position when it moves rearwardly under the impulse of its actuating spring, is independent of both the adjusting means for the spring and the replenishing finger.

In operating upon certain kinds of yarn the tension of the spring 27 may be changed to suit the conditions of yarn being treated, and similarly may the replenishing finger 32 be adjusted independently of both the setting arm and the spring to accord with the character of filling being used for the time being in the loom. This independent adjustability of the several elements of the feeler enables the feeler to be adapted from time to time for use with different kinds or characters of yarn, and adapts the feeler for general use while at the same time maintaining the desired sensitiveness of the feeler either to the presence or substantial exhaustion of filling.

When a working supply of filling is present in the shuttle on a detecting beat, the engaging end of the feeler sinks into the filling mass, and on further frontward movement of the lay, the feeler is moved frontwardly and held from turning or ro-

tative movement by the filling. When, however, the filling has reached substantial exhaustion on a detecting beat, the feeler is again moved forwardly by the forward 5 push of the surface within the shuttle, thereby moving the setting arm 22 from the top portion of the setting cam 23 and permitting the feeler to rotate under the impulse of the spring 27. This rotative movement of the feeler, when the filling is substantially exhausted on a detecting beat, 10 lifts the replenishing finger 32, which in turn moves the transmitter 8 to move the end of the latch 4 into the path of movement 15 of the operating member 5 and thereby effect replenishment of filling.

In the present instance of the invention, the spring 27 is indicated as being both an expansion and torsional spring to impart 20 longitudinal and rotative movement to the feeler.

What is claimed is:—

1. In a feeler motion for looms, the combination of a feeler stand having front and 25 rear bearings, a feeler mounted in said bearings for rotative and longitudinal movements, a spring normally tending to rotate the feeler and hold it in rearward position, a feeler setting arm extending laterally from the feeler in front of the front bearing, a setting cam extending frontward from the feeler stand, a collar adjustably 30 connected to the feeler between the two

bearings and independent of the setting arm, and a replenishing finger secured to 35 the adjustable collar.

2. In a feeler motion for looms, the combination of a feeler stand having front and rear bearings, a feeler mounted in said bearing for rotative and longitudinal movements, a spring normally tending to rotate the feeler and hold it in rearward position, means for adjusting the action of the spring, a feeler setting arm held in fixed relation to the feeler, a setting cam, a collar adjustably secured to the feeler and independent of the feeler setting arm, and a replenishing finger secured to the adjustable collar.

3. In a feeler motion for looms, the combination of a feeler stand, a longitudinally movable and rotatable feeler mounted on the stand, a spring normally tending to rotate the feeler and hold it in rearward position, means for adjusting the rotative and rearward action of the spring, a feeler setting arm and cam, a replenishing finger extending laterally from the feeler and independent of the feeler setting arm, and means for adjusting the replenishing finger 60 independent of the feeler setting arm and spring.

In testimony whereof, I have signed my name to this specification.

ISAAC SNOW.
